[57] CLAIM

The ornamental design for a rotation microtome, as shown.

DESCRIPTION

FIG. 1 is a front elevational view of a rotation microtome showing my new design;

FIG. 2 is a left side elevational view of FIG. 1;

FIG. 3 is a right side elevational view of FIG. 1;

FIG. 4 is a top plan view of FIG. 1; and,

FIG. 5 is a rear elevational view of FIG. 1.

The bottom of the article is substantially plain and unornamented.

Fig. 1
